UNITED STATES PATENT OFFICE.

JOSEPH L. GENDRON, OF WARREN, MASSACHUSETTS.

FOLDING MUSIC-STAND.

No. 824,783.

Specification of Letters Patent.

Patented July 3, 1906.

Application filed October 19, 1904. Serial No. 229,068.

To all whom it may concern:

Be it known that I, JOSEPH L. GENDRON, a citizen of the United States, residing at Warren, in the county of Worcester and State of Massachusetts, have invented a new and useful Folding Music-Stand, of which the following is a specification.

This invention relates to a rack or stand of that class which are employed by musicians for supporting music-sheets or music-books.

The especial objects of this invention are to provide a music-stand which can be folded into smaller compass than music-stands which have heretofore been employed and in which the parts are folded and inclosed within a casing when the music-stand is not in use.

To this end this invention consists of the music-stand and of the combinations of parts therein, as hereinafter described, and more particularly pointed out in the claims at the end of this specification.

In the accompanying drawings, Figure 1 is a front view of the music-stand in its set-up or operative position. Fig. 2 is a side view of the same, showing the music-rack and supporting-legs folded together into position to be pushed into the inclosing tubes. Fig. 3 is a side view showing the inclosing tubes partly folded together. Fig. 4 is a side view showing the music-stand in its folded or closed condition. Fig. 5 is a detail perspective view of the friction-spring for the rod or pipe-section which supports the rack. Fig. 6 is a detail view of the friction-spring at the end of the rod or pipe-section which extends down to the legs. Fig. 7 is a detail view of the hinge which supports the music-rack, and Fig. 8 is a perspective view of the connecting-ferrule for holding the inclosing tubes in line or permitting the same to be folded together.

In that class of constructions to which this invention relates a variety of structures have been employed to provide music-racks which can be folded into small compass when not in use. These structures comprise various arrangements of folding links and supporting-legs. The especial object of my present invention is to provide a neater, more compact, and more attractive form of music-stand, by providing a construction in which all the operating parts will be telescopically inclosed within sections of pipe when the music-stand is not in use. To this end I preferably construct my music-stand with two pipe-sections which are hinged together and which may be held in line with each other when the music-

stand is in use or which can be folded side by side when the music-stand is not in use, and I prefer to have the inclosing tubes of my music-stands hinged together in this manner in order to secure compactness.

Referring to the accompanying drawings and in detail, a music-stand constructed according to this invention, as herein illustrated, comprises the two tubes or pipe-sections 10 and 11. Fitting into the ends of the tubes 10 and 11 are hinge-pieces 12^a, which are shown most clearly by dotted lines in Figs. 3 and 4, which are connected together by a hinge 12. Slidably mounted on the tube 11 is a connecting-ferrule 13, which may be pushed down over the joint between the tubes to hold the tubes in line, as shown in Fig. 2, or may be slid back out of the way to permit the tubes to be folded together, as shown in Fig. 4.

Normally inclosed within the tube 10 are the folding legs, which support the construction. The parts which may be telescopically inclosed within the tube 10 comprise a rod or pipe-section 15, which, as shown in Fig. 6, is provided with a friction-spring 16. The friction-spring 16 comprises a central ring with two extending wings, which are preferably provided with perforations 17 in order to increase the flexibility thereof and which are intended to support the rod or pipe-section concentrically in the tube 10. At its lower end the rod or pipe-section 15 is provided with a head which extends into a lower tube-section 14, which is compressed onto the rod 15, so that the same may slide telescopically thereon. At the lower end of the tube 14 is a bottom piece 18. Pivotedly mounted in the bottom piece 18 are the spreaders or links 19. Mounted on the tube 14 above the bottom piece 18 is a traveler 20, and pivotally connected with the traveler and the spreaders 19 are folding supporting-legs 21. Each of the folding supporting-legs 21 is preferably of an arc-shape section, as shown, and these legs are so supported that when the traveler or ferrule 20 is moved up the legs will be folded close to the pipe-section 14, as illustrated in Fig. 2, the legs when thus folded together being adapted to be pushed up telescopically inside the tube 10 and to be inclosed and retained therein. Normally inclosed within the other tube 11 are the parts which constitute the folding music-rack. These parts comprise a pipe-section 22, having its lower end telescopically com-

pressed onto and inclosing a rod or pipe-section 23. At the lower end of the rod 23, as shown most clearly in Fig. 5, is a friction-spring 24. This friction-spring comprises a hub or tube with extending wings which are preferably perforated at 25 to provide increased flexibility.

The friction-spring illustrated in Fig. 5 is substantially the same as the spring illustrated in Fig. 6, except that its central part is preferably eccentric to leave room inside the casing for the links and connecting parts which form the music-rack, as about to be described.

At its upper end the pipe-section 22, as illustrated in Fig. 7, is provided with a slider 26, and pivoted to the slider 26 is a hinge-piece 27, which supports the music-rack. Extending up from the hinge-piece 27 is a center bar comprising two sections 28 and 29. The upper section 29 can slide or move up and down on the lower section 28. Pivoted near the lower end of the part 28 are arms 30, which form the ledge of the music-rack, and pivoted near the lower end of the upper part 29 are spreaders 31. Connecting the ends of the arms 30 and 31 are two sets of links 32 and 33, and connecting the upper ends of the spreaders 31 with the part 29 are two sets of links 34 and 35. By means of this construction when the parts are extended, as illustrated in Fig. 1, they will constitute a music-rack on which a sheet of music or book can be supported. The linkwork forming this rack may be adjusted or made to assume different shapes according to the size and shape of the sheet of music to be carried.

When the music-rack is to be folded together, the upper part 29 will be slid down upon the lower part 28, so that the pivoted ends of the spreaders 31 will become substantially concentric with the pivoted ends of the arms 30. The parts 30 and 31 may then be folded together substantially in the same manner as the sticks of a fan, the two sets of links 32 and 33 and the two sets 34 and 35 bending in to permit this to be done, so that the rack will fold up, as illustrated in Fig. 2.

The hinge of the piece 27 permits the rack to be brought into alignment with the tube, after which the parts may be pushed telescopically into the inclosing tube 11, as illustrated in Fig. 3, and the completely-folded music-rack can be carried in very small compass, as illustrated in Fig. 4.

One particular advantage in the use of a music-rack as thus constructed resides in the fact that when the music-rack is folded up for transportation all joints and finer parts will be completely inclosed within the tubes and will be protected thereby, so that, although the parts may be of comparatively light and delicate construction, they will not be liable to be bent or injured while in folded condition.

I am aware that many changes may be made in the construction of my folding music-stand by those who are skilled in the art without departing from the scope of my invention as expressed in the claims. I do not wish, therefore, to be limited to the form of music-stand which I have herein shown and described; but

What I do claim, and desire to secure by Letters Patent of the United States, is—

1. In a music-stand, the combination of two inclosing tubes, a hinge connecting said inclosing tubes, a set of supporting-legs fitting telescopically into one of the tubes, and a folding music-rack fitting telescopically into the other of the inclosing tubes.

2. In a music-stand, the combination of two inclosing tubes, a hinge connecting the inclosing tubes, folding supporting-legs fitting telescopically into one of the inclosing tubes, a folding music-rack fitting telescopically into the other of the inclosing tubes, and a sliding ferrule for holding the tubes in line with each other.

3. In a folding music-stand, the combination of a tubular casing, a rod, a friction-piece mounted on one end of the rod and engaging the casing, a tube fitting telescopically onto the other end of the rod, and a set of folding legs mounted on the tube.

4. In a folding music-stand, the combination of a tubular casing, a rod, a friction-piece mounted on one end of the rod and engaging the casing, a tube fitting telescopically onto the other end of the rod, and folding legs mounted on the tube and comprising spreader-arms on the lower end of the tube, a traveler movable up and down on the tube, and legs, each of which is pivotally connected to the traveler and a spreader-arm.

5. In a folding music-stand, the combination of a tubular casing, a rod, a friction-piece on one end of the rod engaging the casing, a tube fitting telescopically onto the other end of the rod, and a folding music-rack carried by the tube.

6. In a folding music-stand, the combination of a tubular casing, a rod, a friction-piece on one end of the rod engaging the casing, a tube fitting telescopically onto the other end of the rod, and a folding music-rack carried by the tube and comprising a slider, a central music-rack rib pivoted to the slider so that the music-rack may be inclined when in use, and additional music-rack ribs adapted to fold close to the central rib when the music-stand is not in use.

In testimony whereof I have hereunto set my hand in the presence of two subscribing witnesses.

JOS. L. GENDRON.
